UNITED STATES PATENT OFFICE.

HOMER HARDCASTLE PENNOCK, OF NEW YORK, N. Y.

DESIGN FOR AN ADVERTISING-DISK.

58,101.

Specification for Design.

Patented June 7, 1921.

Application filed July 25, 1919. Serial No. 313,314. Term of patent 14 years.

To all whom it may concern:

Be it known that HOMER HARDCASTLE PENNOCK, citizen of the United States, residing at 120 Broadway, New York city, New York, has invented a new, original, and ornamental Design for an Advertising-Disk, of which the following is a specification.

The design is shown in accompanying

drawing, in which Figure 1 is a plan view of my disk and Fig. 2 is a sectional view taken along the lines 2—2.

I claim:

The ornamental design for an advertising disk, as shown.

HOMER HARDCASTLE PENNOCK.
